BOILER

Andrew Drummond, St. George, Staten Island, N. Y., assignor to Lehigh Valley Coal Sales Company, New York, N. Y., a corporation of New Jersey

Application April 19, 1944, Serial No. 531,753

7 Claims. (Cl. 122—158)

1

This invention relates to improvements in boiler or furnace construction, particularly to improvements in units of the type suitable for domestic or home heating by means of steam or hot water. However its features are also applicable to installations larger than those of the home heating type.

In my Patent 2,228,757 I have disclosed a boiler construction of a type particularly suitable for use in the heating of homes by means of steam or hot water. That construction is characterized by a lower combustion chamber, and by an upper or hopper portion forming with the combustion zone a boiler and fuel storage assembly arranged in hourglass fashion. Thus, the arrangement includes a constricted neck portion providing a throat or passageway for the transfer of coal between hopper portion and combustion chamber. Each of the two elements of this construction, the hopper and the combustion chamber, are arranged in conical or pyramidal form, the hopper walls in the lower part being inclined to the horizontal at an angle approximately that of the angle of repose of the fuel.

In the construction disclosed in my patent there is also provided a secondary combustion chamber which surrounds the above mentioned throat, and is of substantially triangular vertical cross section and wherein gases evolved from the coal or other fuel utilized are burned. This secondary combustion chamber is connected with the primary combustion chamber by means of tubular conduits, and with the flue gas header leading to the chimney by means of a number of conduits which are also tubular in form and which serve to carry out the products of combustion formed in both combustion chambers.

While the hourglass construction with its surrounding secondary combustion chamber of triangular cross section is very satisfactory in many installations, and while the principles of its operation are admirably adapted for the heating of hot water or the generation of steam by means of coal or other solid fuel, especially in installations of the domestic type, the necessity for providing four reentrant portions to give the hourglass shape has increased the cost of manufacturing units of this type. Moreover, the secondary combustion chamber of triangular cross section is so shaped as to render it and related parts very difficult of construction and assembly. It complicates particularly the problem of forming a firm and leak-proof connection between this chamber and the ends of the tubes which provide the conduits for the escape of the prod-

2

ucts of combustion from the secondary combustion chamber to the chimney. A simple and more effective way of applying such tubes is to insert them in place in the boiler construction, and then roll over or crimp their end portions in order to hold the tubes in position and form the desired tight joint. Because of the limited space provided in the secondary combustion chamber it is difficult, if possible at all, to roll over the ends of the tubes at the point where they enter that chamber when the construction disclosed in my patent is utilized.

In the construction shown in my patent I have also provided a number of ducts arranged in tubular form to provide communication between the primary combustion chamber in the lower half of the hourglass construction and the secondary combustion chamber. While these tubes perform their function very satisfactorily, they add to the cost of the construction and they complicate the problem of cleaning the boiler. These are, of course, factors of considerable importance, especially where the units are intended for home heating purposes.

25 I have now devised a new and improved boiler or furnace construction of the general type shown in my issued patent, which construction involves, however, the simplification of that structure to the end that the boilers may be manufactured more readily and at lower cost than previously possible. Accordingly, it is a main and primary object of this invention to simplify the boiler or furnace construction shown in my issued patent, at the same time retaining its advantages 30 without modifying the principles under which it operates, to the end that the units may be manufactured and maintained more economically than heretofore possible.

Another object of this invention involves the 35 elimination of the four reentrant portions of my former construction, these reentrant portions providing an hourglass shape, and their replacement by a single reentrant portion without, however, surrendering any of the advantages of operation inherent in the arrangement shown in my patent.

A third object of my invention involves modifying the conformation of the secondary combustion chamber wherein the fuel gases are 40 burned before their passage to the chimney so that the endless, triangularly cross-sectioned combustion chamber surrounding the throat of my former construction is replaced by one which is straight and generally trapezoidal in cross section. By this change there is provided adequate

room for the rolling in of the ends of the fire tubes forming the ducts communicating with the flue gas header. By changing the cross-sectional conformation of this secondary combustion chamber and its shape in plan I am also able to secure more satisfactory combustion of the gases in this chamber than previously possible with the triangularly shaped member shown in my issued patent and the cleaning problem is greatly simplified.

A fourth object of this invention involves the simplification of the connection between the main combustion chamber and the secondary combustion chamber whereby the series of tubes previously utilized is replaced by a single large opening, thus permitting free passage of the gases between the combustion chambers. This change not only eliminates the replacement problem present when such tubes are used, but cleaning is also simplified, since ash or dirt readily falls back into the main combustion chamber and does not remain in the connecting conduits.

A fifth object of my invention involves the simplification of the upper storage hopper construction wherein a single boiler plate and not the water space of the boiler as in my issued patent now forms the sides of the hopper. Thus, the only heated surface coming in contact with the fuel in reserve is the sloping bottom 17a. These and still other objects of this invention will be apparent from the ensuing disclosure of certain preferred embodiments thereof.

My invention is best illustrated with reference to the annexed drawings which show a preferred embodiment of a boiler or furnace construction incorporating it. While this description is given in some detail it should be regarded as illustrative, keeping in mind that the inventive principles thereof may be embodied in other types of construction than that illustrated.

In the annexed drawings,

Figure 1 is an elevational view of the improved boiler as seen from the rear.

Figure 2 is a central, longitudinal, vertical section through the boiler taken on line 2-2 of Figure 1 looking in the direction of the arrows.

Figure 3 is a transverse vertical section through the boiler taken on line 3-3 of Figure 2. As shown, this section is taken along a bent line in order that the interior features of the boiler construction may be more adequately illustrated.

Referring now to the drawings, my improved boiler or furnace construction may be said to consist of three principal portions: a base 7 forming the ash pit of the unit; a main boiler portion 8; and a magazine or storage portion 9. The water space of the boiler is located between an outer wall 8a and an inner wall 8b. One side of the inner wall is reentrant and shaped so as to form a combustion chamber 11 and a fuel hopper 12. The base is a box-like member which may be formed of sheet metal or cast iron or steel, suitably bent and welded or otherwise fastened to provide a sturdy supporting structure. The magazine portion 9 may be of sufficient capacity to retain an adequate supply of solid fuel to enable the operation of the boiler continuously over an extended period, twenty four hours or longer.

Turning first to the main boiler section 8, this includes the combustion chamber 11 in which the fuel is ignited and permitted to burn, and the fuel supply member or hopper 12 in open communication with the combustion chamber, the fuel being delivered to the latter from the hopper 12 through the constricted portion or throat 14. The hori-

zontal cross-sectional area of this restricted throat portion 14 may advantageously be less than one-quarter of the horizontal cross-sectional area of the lower portion of combustion chamber 11. As shown in Figure 2, both the fuel storage hopper and the main portion of the combustion chamber are roughly in the form of wedges of generally triangular cross section meeting at the throat 14.

At the lower portion of the combustion chamber there are provided a plurality of grate bars 15 on which the fuel is supported during burning. The angle that the wall 17 of the combustion chamber 11, and its continuation up to the throat, forms with the horizontal is preferably approximately that of the angle of repose of the solid fuel used, thereby insuring that the fuel will entirely fill said combustion chamber and spread out more or less uniformly over the entire area of the lower portion of the combustion chamber so that there will be substantially no air or gas space above the fuel within the combustion chamber and the fuel will not tend to enter the secondary combustion chamber to be hereinafter described. As shown, the hopper 12 is provided with sloping bottom 17a, which is the only heated surface coming in contact with the fuel in the hopper.

Surrounding the combustion chamber 11 and the throat 14, there is provided, as shown, a water jacket or compartment 19 forming the water space of the boiler in which water is heated by means of the heat developed in primary combustion chamber 11 and in secondary combustion chamber 20. As shown, this water space 19 is a rectangular shell in form having a relatively narrow width at three sides of the unit designated by numerals 21, this width increasing at the fourth side and surrounding the flue tubes 22 to the width shown at the right hand end of Figure 2. The water space also partially surrounds the secondary combustion chamber 20, as shown at 23. As shown, the water space 19 is normally filled with water to about the level indicated.

As shown particularly in Figs. 2 and 3, the inclined wall of the upper hopper section is supported by the usual stay bolts 24 and 25. The lower end of the water space 19 is stayed by means of stay bolts 26 running in one direction and stay bolts 27 running in the other direction. The primary combustion chamber is supported transversely by means of stay bolts 29, while stay bolts 31 support the narrower sections 21 of the boiler compartment 19 as shown, for example, at the left hand end in Figure 2 and in Figure 3.

The primary combustion chamber 11 is in direct communication with the secondary combustion chamber 20 through opening 36. As shown, this secondary combustion chamber has a trapezoidal shape in transverse cross section and extends across the boiler compartment. In this combustion chamber gases distilled from the fuel, as well as gases resulting from incomplete combustion in the primary combustion chamber, are burned. On either side of the unit there are provided doors 37 shown in Figures 1 and 3, by which access may be had through the trapezoidal openings 38 to the secondary combustion chamber 20.

The secondary combustion chamber 20 is connected with the flue gas header 40 by means of flue tubes 22. As shown (see Fig. 3), these tubes are arranged across the boiler unit and extend horizontally in a number of rows, the position of the tubes being staggered in successive rows. By means of the doors 37 providing access to the

secondary combustion chamber 20 through openings 38 it is possible to insert a tool for the purpose of rolling over the ends of tubes 22 to hold them firmly in place and form a tight joint. Sufficient room for the insertion of a suitable tool is readily provided by the large cross-sectional area, trapezoidal in shape, of the secondary combustion chamber 20. A tool may also be inserted through clean-out door 43 of flue gas header 40 to permit rolling over the outer ends of tubes 22, thus permitting firm securement of these tubes in place in the boiler and permitting their ready replacement in the event they become burned out. Tubes 22 serve not only to draw off the products of combustion developed in combustion chamber 20, but also the products of combustion developed in primary combustion chamber 11, the primary and secondary combustion chambers communicating, as previously noted, through the opening 36.

The boiler is also provided at its upper portion with a fuel charging opening 47 closed normally by hinged cover 48. Access to the upper surfaces of the grate bars 15 may be afforded through the door 49 but its main purpose is to provide for the admission of air through the sliding grid 49a (if desired) in order to offset the increased resistance of the fuel bed at its greatest depth to the normal penetration of air through the grate. By providing additional air in this manner through the sliding grid 49a, a bright spot normally present on the lower surface of the fuel bed and necessary to ignite the gases distilled from the green fuel as it falls downwards from the upper storage hopper, may be extended upwards along the surface of the fuel bed all the way to the throat in order to accelerate combustion. There is provided grate shaker mechanism including the handle 51 which serves through mechanism not shown to shake the grate bars, thereby permitting the ashes to drop into the ash retainment section 7. Access thereto for the removal of ashes is provided through ash door 52.

The draft regulating arrangement is substantially identical with that shown in my Patent 2,228,758 and includes draft damper 54, normally closed when air is permitted to travel directly through the burning fuel on grate bars 15. This draft damper is positioned in conduit 55 communicating with flue gas header 40 which, in turn, leads to the chimney (not shown) through flue duct 56.

As shown particularly in Figures 2 and 3, the water in the boiler section 19 surrounds the flue tubes 22, thereby deriving heat from the burned gases as they travel from the secondary combustion chamber 20 to the flue gas header 40. There is also positioned in the upper portion of this boiler section, above the flue tubes 22, a series of U-shaped pipes 58 which are connected to a header 59. These pipes serve to hold water for heating, this hot water supply being then withdrawn through header 59. This feature is particularly important when the boiler is designed for domestic or home use as it provides a ready supply of hot water while the heating system is in operation.

The boiler is lagged by the usual insulation, designated generally as 61. It is also provided with the usual relief valve 62 to permit the escape 70 of excessive steam pressure. To provide for the withdrawal of steam from the boiler section 19, and to permit the return of the condensate there-to, there are provided one or more ports 63 above the water level and one or more ports 64 below 75

the water level. Provision for supplying additional water whenever desired, and for draining the boiler, may be made in connection with the pipes leading to one or both of the ports 64. Any of these ports which are not used may be provided with suitable closures, not shown, as usual in boilers. These or other passages communicating with the interior of the boiler may be used for the introduction of auxiliary devices, such as pressure gauges or temperature recording devices, in accordance with practices well understood in the boiler art. As shown most clearly in Figure 1, there is also provided a number of draw-off cocks and water level indicators of a type usual in boilers, these being indicated generally by the numeral 65. Also included is a sight glass 66 of any usual type for observing the level of water in the boiler, valves 67 being provided for controlling access of liquid thereto.

20 Any appropriate means may be provided for regulating damper 54. In the construction shown there is provided damper operating rod 68 extending to either side of the boiler, this rod being adapted for remote operation by mechanism of any suitable type not shown.

25 While a preferred form of the invention has been described in considerable detail it will be understood that various changes may be made in the construction or in the arrangements of

30 the various parts thereof without departing from the general form of the invention. While my invention has been described with particular reference to a boiler for the generation of steam or for heating water, certain features thereof are

35 applicable to other types of furnaces, for example, to those of the hot air type, and it is my intention that my invention shall be construed to cover such modifications. The scope of the invention is therefore not to be restricted to the

40 preferred form and to the detailed description thereof given as illustrative, but is to be construed in accordance with the appended claims.

I claim:

1. In a boiler of the class described, an outer wall structure; inner walls within said outer wall structure, one of said inner walls being provided with a reentrant portion forming with said outer walls a primary combustion chamber of substantially wedge-shaped form and a superposed wedge-shaped fuel storage hopper, said primary combustion chamber and said fuel storage hopper being connected for the passage of fuel therebetween at a restricted throat portion, said reentrant portion providing also a roof for said combustion chamber inclined at a substantial angle and being formed to provide a secondary combustion chamber, said secondary combustion chamber communicating with said primary combustion chamber whereby the products of the combustion may pass therebetween; means providing an additional supply of air to the fuel in said primary combustion chamber whereby incandescence thereof may be controlled; and flue means including tube means providing communication between said secondary combustion chamber and a chimney, said outer wall structure and said inner walls being adapted to retain water around at least portions of said combustion chambers.

2. A boiler according to claim 1 in which the secondary combustion chamber is of substantially trapezoidal cross section.

3. A boiler according to claim 1 in which the tube means comprises a plurality of spaced and substantially parallel tubes.

4. A boiler according to claim 1 in which the restricted throat portion has a horizontal cross-sectional area less than one-quarter of the corresponding area of the lower portion of the primary combustion chamber and in which the roof for the primary combustion chamber is inclined with respect to a horizontal plane at an angle at least equal to the angle of repose of the fuel.

5. In a boiler of the class described, an outer wall structure; inner walls within said outer wall structure, one of said inner walls being provided with a reentrant portion forming with said outer walls a primary combustion chamber of substantially wedge-shaped form and a superposed substantially wedge-shaped fuel storage hopper, said primary combustion chamber and said fuel storage hopper being connected for the passage of fuel therebetween by a restricted throat portion, said reentrant portion providing a roof for said combustion chamber inclined at a substantial angle and also being formed to provide a secondary combustion chamber extending across the interior of the boiler, said secondary combustion chamber communicating with said primary combustion chamber whereby the products of combustion may pass therebetween; and flue means including a plurality of tubes providing communication between said secondary combustion chamber and a chimney, said secondary combustion chamber being sufficiently large to permit the introduction of an edge-turning tool whereby the edge portions of said tubes positioned in said secondary combustion chamber may be turned over to form a tight joint and retain said tubes in place, said outer wall structure and said inner walls being adapted to retain water around at least portions of said chambers.

6. A boiler according to claim 5 in which the

restricted throat portion has a horizontal cross-sectional area less than one-quarter of the corresponding area of the lower portion of the primary combustion chamber and in which the roof for the primary combustion chamber is inclined with respect to a horizontal plane at an angle at least equal to the angle of repose of the fuel.

7. A boiler of the class described comprising an outer wall structure, inner walls within said outer wall structure arranged to provide within the latter a primary combustion chamber, a secondary combustion chamber in direct communication with said primary combustion chamber and closely adjacent thereto, and a fuel storage hopper superposed above said combustion chambers, a substantially horizontal grate at the bottom of said primary combustion chamber, said primary combustion chamber and said fuel storage hopper having at least two vertical walls in substantial alinement and being connected for the passage of fuel therebetween at a restricted throat portion provided by the reentrant formation of certain of the inner walls, said certain of the inner walls forming an inclined bottom for said fuel storage hopper adapted to feed solid fuel therefrom by gravity, said certain of the inner walls also being so formed and arranged as to provide a relatively large primary combustion chamber adapted to be kept constantly filled by gravity flow of fuel from said hopper and a relatively small secondary combustion chamber arranged to receive the gases from said primary chamber, and flue means including tubes providing communication between said secondary combustion chamber and a chimney, said outer wall structure and said inner walls being adapted to retain water around at least portions of said combustion chambers and said tubes.

ANDREW DRUMMOND.
